METHOD OF MAKING SHOE SOLE BLANKS

Harold L. Pierson, Rochester, N. Y., assignor to
E. P. Reed & Co., Rochester, N. Y., a corpora-
tion of New York

Application November 20, 1942, Serial No. 466,385

8 Claims. (Cl. 12—146)

This invention relates to a method of making a shoe sole blank, with particular reference to a leather outer sole composed of a multiplicity of separate cross-pieces united by a supporting layer cemented thereto, and it has for its object to afford a practical, efficient, and economical procedure by which such supporting layer can be readily and securely attached to the separate cross-pieces.

Such a shoe sole blank can be manufactured from small parts of waste leather by cutting therefrom suitably shaped individual cross-pieces which are subsequently assembled into a unitary structure to afford a blank from which the finished outsole can be formed, and one object of the invention is to afford a method by which the cross-pieces can be accurately located in proper relation to each other and held in intimate engagement with each other while the supporting layer is attached.

Another purpose of the invention is to afford a method that insures a permanent and secure attachment between the supporting layer and separate cross-pieces so that while a certain amount of relative movement between adjacent cross-pieces is permitted owing to the flexibility of the supporting layer, the latter remains fixedly attached to the adjacent surfaces of the cross-pieces.

The method involved depends on the use of suitable cement for affixing the supporting layer to the cross-pieces while the latter are held in proper relation within a surrounding positioning form, and it is a further object of the invention to hold the cross-pieces by engaging them at spaced intervals around their periphery, as for instance by means of a corrugated wall affording spaces between the points of contact with the cross-pieces, so that any slight seepage of cement will flow into the spaces between the contact points of the wall, and thus not interfere with accurately positioning the cross-pieces and require only occasional cleaning of the form to rid it of cement.

An additional object of the invention is to afford a method that reduces to a minimum the amount of cement that hardens in the positioning form and brings about a thoroughly effective and permanent union between the supporting layer and cross-pieces by utilizing a pyroxylin sheet between the supporting layer and cross-pieces corresponding in size to the supporting layer.

Still another object of the invention is to afford a method in which the cross-pieces are held

in such a manner by the positioning form that they can be easily removed therefrom after completion of the cementing operation and also quickly and readily inserted into the form previously to the cementing operation.

To these and other ends, the invention consists in the method that will appear clearly from the following description when read in conjunction with the accompanying drawing, the novel features being pointed out in the claims following the specification.

In the drawing:

Fig. 1 is a plan view illustrating the application of the separate cross-pieces composing a leather shoe sole blank to a positioning form with the supporting layer thereon, the intermediate pyroxylin layer between the supporting layer and cross-pieces not appearing since this is the same size as the supporting layer;

Fig. 2 is a longitudinal sectional view on the line 2—2 of Fig. 1 showing the relation of the cross-pieces, with the heel cross-piece in convex position before pressure is applied, and the pyroxylin sheet between the supporting layer and cross-pieces;

Fig. 3 is a sectional view of the positioning form, and

Fig. 4 is a sectional view similar to Fig. 2 showing the relation of the parts as pressure is applied to the supporting layer, pyroxylin sheet, and cross-pieces, to flatten the heel piece and affix the supporting layer.

The present invention is in the nature of an improved method for manufacturing a leather shoe sole blank to be used in the production of a shoe sole and shoe such as disclosed in my pending application Serial No. 441,003, filed April 29, 1942, which discloses an outer sole composed of a multiplicity of separate cross-pieces held together in a unitary assembly by means of a supporting layer cemented thereto.

Referring more particularly to the drawing in which like reference numerals refer to the same parts throughout the several views, the shoe sole blank is composed of a suitable number for instance five separate leather cross-pieces which can be readily die-cut from small portions of leather heretofore generally regarded as waste material, and in the embodiment shown, these include a toe portion cross-piece 1 that has parallel front and back edges 2 and 3 respectively and converging side edges 4. 5 designates an intermediate cross-piece that is preferably of rectangular formation as shown in Fig. 1, 6 is a ball portion cross-piece, 7 is an instep portion cross-

piece that is preferably of rectangular formation, and 8 is a heel portion cross-piece extending from the instep portion cross-piece 7 to the rear end of the form, the heel portion cross-piece 8 being preferably of greater length from front to rear than the remaining cross-pieces for a purpose that will appear presently.

Referring to Fig. 2, the cross-pieces are positioned so that the grain side of the leather is on the bottom and constitutes the exposed surface of the finished outsole, and the cross-pieces are transversely indented or grooved as at 9 to give an effect on the finished sole of narrow transverse strips of approximately uniform width, the grooves 9 simulating in appearance the joints between the separate cross-pieces.

In order to hold the cross-pieces in proper relationship during cementing of the supporting layer, they are arranged within a positioning form that engages their outer edges or periphery at spaced intervals, and this is preferably accomplished by a form that includes a base plate 11, having an opening 12 at its rear end for a purpose that will be explained later, and provided with an upstanding vertically corrugated wall 13 of approximately the same height as the thickness of the leather cross-pieces.

The wall 13 is formed of a transversely corrugated flexible metal ribbon or strip that is secured edgewise to the base plate 11 by solder 14, spot-welding, or in any other suitable fashion, the wall 13 being arranged on the base plate 11 so as to conform to the shape of the finished shoe sole blank to be produced and of the several cross-pieces already described when they are assembled into the desired completed relationship. It is to be understood that the cross-pieces are cut to predetermined size and shape to fit a given positioning form, and that a separate form is provided for each different size of shoe sole blank.

The total length of the cross-pieces from front to rear is slightly greater than the length of the positioning form or the space which they finally occupy, such excess length being afforded preferably in the heel portion cross-piece 8 which can be slightly convexed when first positioned in the form owing to its greater length, as shown in Fig. 2, and is flattened in the form when pressure is applied, as shown in Fig. 4, thereby forcing all the cross-pieces slightly endwise of the form and crowding them into intimate contiguous relationship.

The supporting layer 16 is cut from a leather split or other suitable thin flexible material to predetermined form, as shown in Fig. 1, with its front edge 17 conforming to the front edge of the toe portion cross-piece 1 and of the positioning form, and is cemented to the cross-pieces by the application of cement and pressure. This is preferably attained by interposing a pyroxylin sheet or wafer 18 between the supporting layer 16 and the cross-pieces after first dipping the pyroxylin sheet in any desired softening solution to activate it suitably for attachment.

The pyroxylin sheet is cut to approximately the same size as the supporting layer 16, which latter extends over the forward part of the heel portion cross-piece 8 and all of the other cross-pieces, and the positioning form with the parts applied as described is then placed in a suitable press and pressure applied through a rubber pad 19, see Fig. 4, which results in flattening the heel portion cross-piece 8 and securely affixing the supporting layer to the several cross-pieces.

After the positioning form is removed from the press, the blank can readily be ejected by applying a finger through the opening 12 to push the blank out of engagement with the surrounding side wall 13 of the form. This removal of the blank from the form is facilitated because the leather cross-pieces are engaged only at spaced intervals around the periphery by the inwardly extending corrugations of the wall 13, which arrangement also quickly facilitates the positioning of the cross-pieces in the form.

A further advantage in engaging the cross-pieces only at spaced intervals by the utilization of a corrugated wall lies in the fact that when pressure is applied, if any cement exudes from between the supporting layer and cross-pieces, it finds its way into the spaces afforded between the corrugations of the surrounding wall and thus does not affect the efficiency of the form for succeeding operations. With this arrangement, it is necessary to clean the form and remove hardened cement only at infrequent intervals, and the spaced contact points are always available for correct positioning of the leather cross-pieces. This has a further distinct advantage as contrasted with a form having a straight engaging side wall which would have continuous engagement with the periphery of the leather blank, as the latter quickly clogs with exuded cement, requires too frequent cleaning, makes it more difficult both to position the leather cross-pieces and remove the finished blank, and is unfitted commercially for carrying out the procedure as indicated.

While the invention has been described with reference to certain particular steps in procedure, it is not confined to the exact details of the method as disclosed, and this application is intended to cover such departures or modified operations as may come within the purposes of the improvement or the scope of the following claims.

I claim:

1. The method of making a shoe sole blank from a multiplicity of separate cross-pieces, which includes arranging said cross-pieces within a surrounding positioning form in juxtaposition to each other, said cross-pieces having a slightly greater total length than that of the form and one of said cross-pieces being arranged in the form in convex position, cementing a supporting layer to the cross-pieces, and applying pressure against the supporting layer and cross-pieces whereby the convexed piece is flattened in the form forcing all the cross-pieces into intimate contiguous relation and the supporting layer is permanently attached to the cross-pieces.

2. The method of making a shoe sole blank from a multiplicity of separate cross-pieces, which includes arranging said cross-pieces within a surrounding positioning form in juxtaposition to each other, positioning a supporting layer over the cross-pieces with a pyroxylin sheet between it and the cross-pieces, and applying pressure against the supporting layer, pyroxylin sheet, and cross-pieces to attach the supporting layer permanently to the cross-pieces.

3. The method of making a shoe sole blank from a multiplicity of separate cross-pieces, which includes arranging said cross-pieces within a surrounding positioning form in juxtaposition to each other, said cross-pieces having a slightly greater total length than that of the form and one of said cross-pieces being arranged in the form in convex position, positioning a supporting layer over the cross-pieces with a pyro-

ylin sheet between it and the cross-pieces, and applying pressure against the supporting layer, pyroxylin sheet, and cross-pieces whereby the convexed piece is flattened in the form forcing all the cross-pieces into intimate contiguous relation and the supporting layer is permanently attached to the cross-pieces.

4. The method of making a shoe sole blank from a multiplicity of separate cross-pieces, which includes arranging said cross-pieces in juxtaposition to each other and holding them in such position by engagement at points spaced around their periphery, positioning a supporting layer over the cross-pieces with a pyroxylin sheet between it and the cross-pieces, and applying pressure against the supporting layer, pyroxylin sheet, and cross-pieces whereby the supporting layer is permanently attached to the cross-pieces.

5. The method of making a shoe sole blank from a multiplicity of separate cross-pieces, which includes arranging said cross-pieces in juxtaposition to each other and holding them in such position by engagement of a surrounding corrugated wall of a positioning form, said corrugated wall affording spaces between the points of contact with the cross-pieces, cementing a supporting layer to the cross-pieces, and applying pressure to the supporting layer and cross-pieces to attach said parts permanently.

6. The method of making a shoe sole blank from a multiplicity of separate cross-pieces, which includes arranging said cross-pieces in juxtaposition to each other and holding them in such position by engagement of a surrounding corrugated wall of a positioning form, said corrugated wall affording spaces between the points of contact with the cross-pieces, the cross-pieces having a slightly greater total length than that of the form and one of said cross-pieces being arranged in the form in convex position, cement-

ing a supporting layer to the cross-pieces, and applying pressure against the supporting layer and cross-pieces whereby the convexed piece is flattened in the form forcing all the cross-pieces into intimate contiguous relation and the supporting layer is permanently attached to the cross-pieces.

7. The method of making a shoe sole blank from a multiplicity of separate cross-pieces, which includes arranging said cross-pieces in juxtaposition to each other and holding them in such position by engagement of a surrounding corrugated wall of a positioning form, said corrugated wall affording spaces between the points of contact with the cross-pieces, positioning a supporting layer over the cross-pieces with a pyroxylin sheet between it and the cross-pieces, and applying pressure against the supporting layer, pyroxylin sheet, and cross-pieces whereby the supporting layer is permanently attached to the cross-pieces.

8. The method of making a shoe sole blank from a multiplicity of separate cross-pieces, which includes arranging said cross-pieces in juxtaposition to each other and holding them in such position by engagement of a surrounding corrugated wall of a positioning form, said corrugated wall affording spaces between the points of contact with the cross-pieces, the cross-pieces having a slightly greater total length than that of the surrounding form and one of said cross-pieces being arranged in the form in convex position, positioning a supporting layer over the cross-pieces with a pyroxylin sheet between it and the cross-pieces, and applying pressure against the supporting layer, pyroxylin sheet, and cross-pieces whereby the convexed piece is flattened forcing all the cross-pieces into intimate contiguous relation and the supporting layer is permanently attached to the cross-pieces.

HAROLD L. PIERSON.
